UNITED STATES PATENT OFFICE.

JOSEPH BIJUR, OF NEW YORK, N. Y.

IGNITION APPARATUS FOR INTERNAL-COMBUSTION ENGINES.

1,261,345.

Specification of Letters Patent.

Patented Apr. 2, 1918.

Application filed March 9, 1915. Serial No. 13,135.

To all whom it may concern:

Be it known that I, JOSEPH BIJUR, a citizen of the United States, and residing at 122 East 60th street, N. Y., in the county of New York and State of New York, have invented a new and Improved Ignition Apparatus for Internal-Combustion Engines, of which the following specification is a full disclosure.

10 This invention relates to ignition apparatus for internal combustion engines and more particularly for those engines liable to frequent speed changes such as are employed in motor vehicles.

15 One of the objects thereof is to provide practical apparatus of the above type in which efficient action is attained under all conditions of use. Another object is to provide apparatus of the above type of 20 simple construction and the most reliable automatic action. Another object is to provide apparatus having the above characteristics in which objectionable effects of varying engine speed upon the ignition of the 25 engine are done away with. Other objects will be in part obvious and in part pointed out hereinafter.

This invention accordingly consists in the 30 features of construction, combinations of elements and arrangement of parts which will be exemplified in the construction hereinafter described and the scope of the application of which will be indicated in the following claims.

35 In the accompanying drawing in which is illustrated one of various possible embodiments of this invention,

Figure 1 is a diagrammatic plan of the 40 same, certain parts being shown in section in order to disclose the construction more clearly.

Fig. 2 is a diagrammatic view indicating one stage of action of the parts.

Figs. 3, 4 and 5 are similar views showing successive stages of action of these parts.

Similar reference characters refer to similar parts throughout the views of the drawing.

Referring now to Fig. 1 of the drawings, 50 there is shown at 1 a storage battery or other source of current, and from the lead 2 of which the circuit passes through the primary coil 3 of an induction coil 4, the secondary coil 5 of which is operatively connected with the ignition devices diagram-

matically indicated at 6. From this point the circuit leads to a contact screw 7 by means of the adjustable contact 8 coacting with a contact 9 upon a pivoted oscillatory lever 10 and a spring 11. The mechanical 60 as well as electrical action of the parts last referred to will be later described, but it may here be noted that they constitute an interrupting device which is shunted by the condenser 12, the latter performing its ordinary well known functions.

A parallel electrical circuit leads from the same terminal of battery 1 through the resistance element 13, screw 14, pivoted lever 15, contacts 16 and 17, lever 10 and spring 70 11 to the screw 7. The contacts 16 and 17 form an interrupting device for this branch which may be shunted by a high resistance 18 or a condenser to reduce sparking. From the screw 7 the above circuits are joined and led serially through a conductor 19 and an inductance coil 20 to the remaining terminal of the battery. Inductance coil 20 is of such a nature as to have a large self-inductive effect and is so arranged as to be 80 adjustable in inductance either by varying the number of coils in circuit, as by the swinging contact 20^a, or adjusting the reluctance of the circuit of its magnetic field.

Turning now to the interrupting apparatus, it may first be noted that the term "interrupter" is used throughout this description and the following claims in a broad sense to denote any device acting periodically to break or vary an electric 90 current.

Casing 21 is mounted upon any suitable bearing, as indicated by the dotted line 22, so as to swing about the axis of the shaft 23 and there are provided an arm 24 and manually actuated means 25 to swing this casing angularly and thus vary the time of action of the interrupting devices with respect to the angular position of the shaft 23, the latter being driven in fixed relation to 100 the crank shaft of the engine.

In this manner, the ordinary manual advance or retardation of the time of ignition with respect to the position of the piston may be gained.

Mounted upon shaft 23 is a cam 26 which coacts with the cam roller 27 and oscillates the lever 15 pivoted at 28, the latter being held firmly against the cam by the spring 29. The above operation of lever 15 causes 110

it to swing contact 16 into engagement with the contact 17 and in turn swing the lever 10 about the axis 30 to move contact 9 out of engagement with contact 8 and interrupt 5 the main circuit through the ignition coil 3.

Considering now the action of this apparatus and assuming that the ignition circuit be closed as by the hand switch 31, it will be assumed that the roller 27 is resting 10 within one of the recesses 32 of the cam 26. With the parts in this position, the spring 29 will have retracted contact 16 from contact 17 and permitted the spring 11 to throw contact 9 into engagement with contact 8. This 15 position of the parts is diagrammatically indicated in Fig. 2 of the drawing. As the cam 26 now rotates, one of its projections engages and throws outwardly the roller 27, swinging contact 16 toward contact 17. The 20 instantaneous engagement of these parts is depicted in Fig. 3 of the drawing, but it is to be understood that the time of this connection is extremely minute as the lever 15 is swinging rapidly and instantly upon its 25 engagement throws the lever 10 toward the position indicated in Fig. 4 of the drawing, in which contacts 8 and 9 are separated. As the roller 27 rides over the cam projection, the lever 15 under the action of spring 29 30 quickly swings in a reverse direction, the instantaneous position in which it permits contact 9 to engage contact 8 before contact 16 has left contact 17 being shown in Fig. 5 of the drawing. The movement, however, of 35 lever 15 toward the left is quickly continued until the parts again attain the position indicated in Fig. 2 of the drawing, and this cycle of operations is repeated as each cam projection comes into engagement with the 40 roller 27.

Turning now to the electrical action of this apparatus, this will perhaps be best understood by a consideration in the first place of the position shown in Fig. 1 of the drawing. In this position, the switch 31 being 45 closed, there is a circuit from battery 1 through inductance coil 20, contacts 16 and 17 and the resistance 13. The flow of current in this circuit builds up the magnetic 50 field of the coil 20. The next operative position of the parts is shown in Fig. 2 of the drawing after they have passed through the position indicated in Fig. 5, the latter position, as above noted, being assumed for such 55 an extremely short time that it is without effect. As shown in Fig. 2, the circuit through coil 20 and resistance 13 is broken at the contacts 16 and 17, the resistance 18 being of such an excessively high value as 60 to afford no substantial path for the current. The breaking of this circuit causes a tendency of the magnetic field or lines of force of the inductance coil 20 to collapse which, as is well known, generates an instantaneous 65 electro-motive force of high voltage in the

direction in which the current has been flowing. It is unnecessary to go into the details of this action as it is the well-known "extra current" or tendency of a current to persist in an inductive circuit after the circuit has been interrupted. This self-inductive current here finds an outlet through the lever 10, contacts 9 and 8 and primary coil 3, and thus tends instantaneously to force a current through the latter coil. As above 70 described the apparatus is in the position shown in Figs. 3 and 5 for but an inappreciable amount of time so that its effect may be substantially neglected. It should be noted, however, that in this position the current from the battery 1 will take the easier path through contacts 16-17 rather than that through contacts 8-9 and coil 3. It is, therefore, clear that coil 20 will build up 75 before coil 3. The closing of contacts 8 and 9, however, completes a circuit through coil 3, as hereinafter described, which tends to force a current through this coil in the same direction as the inductive electro-motive force of coil 20. If the circuit were merely 80 completed from the battery 1 through the coil 3 as by an interrupter, there would be a substantial lag in building up the current in the latter coil, due to its inductance. The effect of this lag in ordinary apparatus 85 would be such that with high engine speeds and a correspondingly high speed of the interrupter, the circuit might well be successively interrupted before the current in coil 3 is able to gain its full effective value. 90 Also, if the parts were so arranged and proportioned that a satisfactory current value in coil 3 would be obtained at the highest engine speed, then at low engine speeds, when there is a sufficiently long period of contact to 95 permit the current to overcome the inductive effect, the current value reached might be harmful in its heating and arcing effect. In the present case, however, even at the highest engine speeds, an ample current in coil 3 100 is provided due to the above-described inductive discharge of the coil 20 which, so to speak, "kicks" the current in coil 3 up to its desired value. In this manner, the inductive 105 effect of coil 20 is made to neutralize the undesirable inductive effect of coil 3 and the ignition is entirely satisfactory, even at the highest engine speeds. It may also be noted 110 that as there is a collapse of the magnetic field coil 20 to gain this inductive E. M. F., there may be at slow engine speeds, and consequent long periods of contact, an increase 115 of current above its minimum value, which builds up the field of coil 20, and hence the inductance of the latter coil not only aids by bolstering up the current in coil 3 at high engine speeds, but by opposing the current in this circuit at low engine speeds during 120 the later stages of contact, when it might otherwise reach a higher value. 130

It will thus be seen that there is provided apparatus in which the several objects of this invention are achieved.

As many changes might be made in the 5 above construction, and as many apparently different embodiments might be made of this invention without departing from the scope thereof, it is intended that all features herein described or shown in the accompanying 10 drawings shall be interpreted as illustrative and not in a limiting sense.

Having thus revealed this invention, I claim as new and desire to secure the following combinations of elements, or equivalents 15 thereof, by Letters Patent of the United States:—

1. In ignition apparatus for internal combustion engines, in combination, a source of current, a coil connected therewith, a second 20 coil, and means adapted to utilize the inductance of said second coil to reduce the effect of the inductance of said first coil.

2. In ignition apparatus for internal combustion engines, in combination, a source of 25 current, a coil connected therewith, a second coil, and means adapted to utilize the inductance of said second coil to neutralize the effect of the inductance of said first coil.

3. In ignition apparatus for internal combustion engines, in combination, a source of 30 current, a coil connected therewith, a second coil, means adapted to utilize the inductance of said second coil to neutralize the effect of the inductance of said first coil, and 35 means adapted to adjust the effective inductance of said second coil.

4. In ignition apparatus for internal combustion engines, in combination, a source of current, a coil connected therewith, an inter- 40 rupter in circuit with said source of current and said coil, a second coil connected to receive current, and means adapted to cause said second coil to discharge its self-inductive current through said first coil as the 45 circuit through the latter is periodically completed by said interrupter.

5. In ignition apparatus for internal combustion engines, in combination, a source of current, a coil, means connecting said coil 50 with said source of current, and means adapted as said coil is connected to generate a momentary electro-motive force in the direction of flow of current in said coil.

6. In ignition apparatus for internal combustion engines, in combination, a source of current, a coil serially connected with said source of current, a pair of branches in series with said coil and in parallel with each other, a coil in one of said branches, and 60 means adapted alternately and oppositely to vary the current in said branches.

7. In ignition apparatus for internal combustion engines, in combination, a source of current, a coil serially connected with said 65 source of current, a pair of branches in series

with said coil and in parallel with each other, a coil in one of said branches, and means adapted alternately to interrupt the current in said branches.

8. In ignition apparatus for internal combustion engines, in combination, a source of current, a coil serially connected with said source of current, a pair of branches in series with said coil and in parallel with each other, a coil in one of said branches, and 70 means adapted alternately to interrupt the current in said branches and connect both branches in parallel prior to each interruption.

9. In ignition apparatus for internal combustion engines, in combination, a source of current, a coil serially connected with said source of current, a pair of branches connected with said source of current in parallel with each other, a coil in one of said branches, a pair of relatively separable coacting contacts in one of said branches, a pair of relatively separable coacting contacts in the other of said branches, a movable member having one contact of each pair 85 mounted thereon, a movable member having the remaining contact of one pair mounted thereon, and means adapted intermittently to move said second member and thereby bring its contact into engagement with one 90 of the contacts of said first member and move the second contact of said first movable member out of engagement with the contact with which it coacts.

10. In ignition apparatus for internal combustion engines, in combination, a source of current, a coil serially connected with said source of current, a pair of branches connected with said source of current in parallel with each other, a coil in one of said 100 branches, a pair of relatively separable coacting contacts in one of said branches, a pair of relatively separable coacting contacts in the other of said branches, a movable member having one contact of each pair 105 mounted thereon, a movable member having the remaining contact of one pair mounted thereon, means adapted intermittently to move said second member and thereby bring its contact into engagement with one of the 110 contacts of said first member and move the second contact of said first movable member out of engagement with the contact with which it coacts, and resilient means connected to oppose the said movements of the 115 said movable members.

11. In ignition apparatus for internal combustion engines, in combination, a source of current, a coil serially connected with said source of current, a pair of branches in series 125 with said coil and in parallel with each other, a coil in one of said branches, a pair of relatively separable coacting contacts in one of said branches, a pair of relatively separable coacting contacts in the other of 130

- said branches, a movable member having one contact of each pair mounted thereon, a movable member having the remaining contact of one pair mounted thereon, and a rotary cam positioned and driven to move said second member and thereby bring its contact into engagement with one of the contacts of said first movable member and move the other contact of said first movable member
- 10 away from the contact with which it coacts.
12. In ignition apparatus for internal combustion engines, in combination, a source of current, a coil serially connected with said source of current, a pair of branches in series with said coil and in parallel with each other, a coil in one of said branches, a pair of relatively separable coacting contacts in one of said branches, a pair of relatively separable coacting contacts in the other of said branches, a movable member having one contact of each pair mounted thereon, a movable member having the remaining contact of one pair mounted thereon, and a rotary cam positioned and driven
- 20 to move said second member and thereby bring its contact into engagement with one of the contacts of said first movable member and move the other contact of said first movable member away from the contact with which it coacts, said movable members being mounted to swing as they move about pivotal points.
13. In ignition apparatus for internal combustion engines, in combination, a source of current, a coil serially connected with said source of current, a pair of branches in series with said coil and in parallel with each other, a coil in one of said branches, a pair of relatively separable coacting contacts in one of said branches, a pair of relatively separable coacting contacts in the other of said branches, a movable member having one contact of each pair mounted thereon, a movable member having the remaining contact of one pair mounted thereon, a rotary cam positioned and driven to move said second member and thereby bring its contact into engagement with one of the contacts of said first movable member and move the other contact of said first movable member away from the contact with which it coacts, said movable members being mounted to swing as they move about pivotal points, and resilient means resisting the said movements
- 55 of said movable members.
14. In ignition apparatus for internal combustion engines, in combination, an electric circuit comprising a coil and an interrupter, and electrical means adapted to prevent decrease of the value which the current in said coil attains as the speed of said interrupter increases.
15. In ignition apparatus for internal combustion engines, in combination, an electric circuit comprising a coil and a source of current, a device for periodically varying the current in the said coil, a second coil carrying current from said source of current, and means for utilizing the inductance of said second coil to offset the effect of the inductance of said first coil.
16. In ignition apparatus for internal combustion engines, in combination, an electric circuit comprising a member having a substantial inductance, means for periodically varying the current in said member, and electrically actuated means for compensating for the effect of the inductance of said member in tending to lessen the value which the current therein reaches as the speed of said varying means increases.
17. In ignition apparatus for internal combustion engines, in combination, a source of current, an interrupter and a primary coil serially connected with said source of current, a secondary coil operatively related to said primary coil, means adapted to drive said interrupter at varying speeds, and means adapted to neutralize the inductance of said primary coil.
18. In ignition apparatus for internal combustion engines, in combination, a source of current, an interrupter and a coil connected with said source of current, means adapted to oppose the rise of current in said coil, and means adapted to render said opposing means operative subsequent to the closing of the circuit through said coil.
19. In ignition apparatus for internal combustion engines, in combination, a source of current, an interrupter and a coil connected with said source of current, means adapted to oppose the rise of current in said coil, and means adapted to render said opposing means operative at a predetermined period subsequent to the closing of the circuit through said coil.
20. In ignition apparatus for internal combustion engines, in combination, a source of current, an interrupter and a coil connected with said source of current, means adapted to oppose the rise of current in said coil, means adapted to render said opposing means operative subsequent to the closing of the circuit through said coil, and means adapted to adjust the time of action of said opposing means.

In witness whereof I hereunto subscribe my name as attested by the two subscribing witnesses.

JOSEPH BIJUR.
